UNITED STATES PATENT OFFICE.

ERNST J. BERG, OF SCHENECTADY, NEW YORK, ASSIGNOR TO GENERAL ELECTRIC COMPANY,
A CORPORATION OF NEW YORK.

ELASTIC-FLUID TURBINE.

No. 910,164.

Specification of Letters Patent. Patented Jan. 19, 1909.

Application filed April 20, 1907. Serial No. 369,252.

To all whom it may concern:

Be it known that I, ERNST J. BERG, a citizen of the United States, residing at Schenectady, county of Schenectady, State of New York, have invented certain new and useful Improvements in Elastic-Fluid Turbines, of which the following is a specification.

My invention relates to elastic fluid turbines driving electric generators and other loads, and has for its object to improve the construction and arrangement of such apparatus and at the same time overcome certain of the defects and losses found therein as heretofore constructed and arranged.

In carrying out my invention I divide the turbine into stages of expansion, each with moderate fluid velocities, so as to avoid excessive bucket speeds. In each stage of the simplest form of the invention are located two bucket wheels mounted to revolve in opposite directions, one wheel receiving steam or other elastic fluid directly from a nozzle or other fluid-discharging device, the other receiving its supply from the first-mentioned wheel. One wheel of each stage is mounted on its individual shaft which extends outwardly from the inclosing casting, and the remaining wheels are mounted on a shaft common thereto and extending between the casings. By reason of this construction the use of shafts located one inside of the other and the consequent disadvantages are avoided.

The shafts for the wheels are preferably located in axial alinement, and are carried by suitable bearings mounted on a bed-plate or other support. Since these wheels are separate and are not in engagement with each other, absolute alinement is unnecessary, although desirable. The buckets of the wheels are properly designed to extract the velocity of the fluid stream due to the nozzles by successive operations. In an arrangement of this kind, the losses due to fixed or intermediate buckets are avoided because the fluid flows directly from one wheel to the other. The velocity of the fluid leaving the nozzle or nozzles can be relatively high without having unduly high bucket speeds, because of the fact that the buckets rotate in opposite directions. In a turbine of this character the first wheel, or the one directly receiving the motive fluid,

develops a materially greater torque than does the second wheel. The distribution of work between the two wheels in a given stage depends upon the relative spouting velocity of the motive fluid, the bucket shapes and the bucket speed.

Tests made on a turbine constructed in accordance with my invention show that with a given amount of energy and a bucket speed for each wheel of 560 feet per second, the work performed by the first or primary wheel will be about 70% of the total and the remaining or secondary wheel about 30%. These figures are given merely as illustrations and not limitations of the fact that the wheels develop different torques. An increase in bucket speed will cause the primary wheel to do somewhat more work and the secondary wheel less. A decrease in bucket speed has the opposite effect. To state the matter in another way, the ratio between the two wheels as to the work performed changes with changes in bucket speed for the same available energy, and for the same speed with changes in available energy. The difference in torque developed by the two wheels of such a combination has long been considered a serious drawback and attempts have been made to avoid it but without success. To compensate for the difference in torque the wheel of the first stage developing the lesser torque may be connected to the wheel of a succeeding stage having a greater torque, the other wheels driving individual loads. For example, in a two-stage four-wheel combination, the first wheel may drive an individual load such as the revolving member of an electric generator unit, and so may also the last, while the remaining or intermediate wheels may be connected in a manner to drive as a common load the revolving element of another generator unit. Such an arrangement results in three independent units whose power in the aggregate may be very large without however imposing thereon conditions inimical to safe design.

My invention, with respect to the arrangement of the generator units, is exceedingly flexible, since by combining the parts in various ways, the output of any particular generator unit can be made to be relatively large or small as conditions demand. Since

the primary wheels develop considerably more power than the secondary wheels, it is evident that for a given total output a combination of two primary wheels driving the 5 intermediate or central unit will, when properly designed, give the maximum power; a primary and a secondary wheel, other things being equal, will give less power, and two secondary wheels will give still less 10 power. The same holds true for the outside or end units. When they are driven by primary wheels, they will develop the maximum power and when driven by secondary wheels, other things being equal, a lesser amount of 15 power. This is a very important factor where the turbine is employed to drive a generator since it enables me to produce by a combination of different types of units a much larger turbo-generator than is possible 20 with the ordinary types of apparatus where one generator supplies all of the current, since for certain speeds some of these machines are limited to small units.

The synchronous alternating-current generator, usually having a distributed stationary armature winding and a revolving field structure, the coils of which are excited from a suitable source of direct current, is limited in size for a given speed by mechanical considerations. In so far as present designs are concerned, for machines running at 3600 R. P. M. the upper limit is about 750 kilowatts. With lower speeds the output can of course be increased, but by reason of the 35 more efficient extraction of energy, it is desirable to use relatively high bucket speeds without abnormally large diameter on account of the great centrifugal stresses developed under such latter condition.

40 Assuming that the stages do equal amounts of work and that the first unit, considered from left to right, is driven by a primary wheel, the second unit by a secondary and a primary wheel and the third unit by a secondary wheel: the first unit would, for a given bucket speed and available energy, develop 30% of the total, the second 50% and the third 20%. Now, assuming that the limit in size of a synchronous machine for 45 the given shaft speed is 750 kilowatts, the third or last unit will be of 750 kilowatts output; the second unit would be $\frac{5}{6} \times 750 = 1875$ kilowatts, and the first unit $\frac{3}{6} \times 750 = 1125$ kilowatts. The first and second units would 50 therefore be of the induction type, the third of the synchronous type and the total output at normal load for the given speed would be 3750 kilowatts, or five times as large as a machine of the ordinary synchronous type with the limits now imposed 55 in the design.

The induction alternator, depending for its excitation upon alternating current derived from a suitable source, is well adapted

60 to large outputs at high speeds, since the rotating member can be of the squirrel-cage type and therefore capable of high shaft as well as peripheral speed. It is, however, necessary to have some alternating current source of supply to furnish the excitation. 65 When induction and synchronous units are combined, the latter will supply the current for exciting the former. Instead of making the stages perform equal amounts of work, one or the other may perform a 70 larger amount, while the ratios between the units may also be changed.

In order that the generator units may supply current to a common load, such as the bus-bars on the switch-board in a power 80 station, they are wound to deliver current at the same potential. When all are of the synchronous alternating-current type and properly connected in multiple to the load, they will as is well known run at 85 the same speed because the tendency of one machine to go faster or slower than normal is opposed by the current generated in other units in circuit. When synchronous and induction generators are connected in multiple they will operate in electrical 90 synchronism and very nearly, although not exactly, in mechanical synchronism. In the case of direct-current machines, I may tap the armature of each machine at 95 suitable points and run multiphase connections between the units, which connections will keep the machines running at the same speed, and hence all will deliver current at the same potential. These connections form 100 what may be termed an electrical gearing between the generator units, since the action is to maintain the same speed for all of the machines, and each machine contributes its share towards supplying the total amount 105 of current required. Since these connections may be depended upon in alternating or direct-current machines to maintain the same or substantially the same speed for all of the generator units, it follows that it is 110 only necessary to govern the admission of motive fluid to one stage and the other will take care of itself, although such an arrangement does not necessarily preclude the 115 use of a governing mechanism for the second stage where high economy is a factor of more importance than the additional first cost and that of maintenance.

My invention is directed principally to 120 turbine generators containing means therein for causing them to run in synchronism or substantially in synchronism with the other units, but instead of providing each generator unit or member with such means and forming a part thereof, separate means may 125 be provided for the purpose. Such an arrangement is particularly useful where the turbine drives members other than electrical

910.161

generator units. In this case each turbine shaft may be provided with a small generator unit and the necessary connections and slip-rings between moving and stationary parts to cause the shafts to run at the same speed.

In the accompanying drawings, which illustrate embodiments of the invention, Figure 1 is an axial section of a turbine of the jet or impact type having oppositely rotating bucket wheels; Fig. 2 is a more or less diagrammatic view showing a two-stage turbine of the type set forth in Fig. 1 connected to three electric generator units with the intermediate unit arranged to develop the major portion of the electric energy, the two outside units being smaller and hence of reduced capacity; Fig. 3 is a more or less diagrammatic view similar to the above but with a different distribution of the turbine parts to develop different torques; Fig. 4 is a similar view showing the turbine parts arranged to develop more nearly equal torques; Fig. 5 shows still another arrangement of parts for the same purpose; Fig. 6 is a diagram showing two induction and one synchronous alternating-current three-phase generator units connected to a common load, in such manner as to control their speed relation; Fig. 7 shows a suitable arrangement for direct-current machines; Fig. 8 is a diagrammatic view of an induction type alternating current generator; and Fig. 9 a synchronous type alternating current generator.

Referring to Fig. 1, 1 and 2 represent wheels, each having a row of peripheral buckets 3, the buckets of one wheel being shaped to rotate in one direction and those of the other wheel in the opposite direction. Steam or other elastic fluid is admitted to the first wheel by an expanding or non-expanding nozzle 4 as the conditions require. The nozzle is or may be provided with separate passages or sections which may be cut into and out of service to vary the admission of fluid to meet the load requirements. In some cases a throttling governor may be provided. The wheels are inclosed in a casing 5 which is divided in a plane passing between the wheels. The nozzle or other discharging device is bolted to one-half of the casing and the other half is provided with an exhaust chamber 6 connected by a conduit 7 with another stage or with a condenser depending on whether it is a high- or a low-pressure stage. Motive fluid is admitted by a conduit 8 leading from the boiler, superheater or other source of supply. This conduit discharges into a chamber or chest 9 and the latter supplies the nozzle passages. To simplify the illustration, the governing mechanism has been omitted but it is to be understood that I may use one of any suitable construction.

The wheel disks may be made solid or of any other suitable construction and each is provided with a hub 10 bolted to the side thereof so that the wheels may be located close together. The hubs are bored to receive the inner ends of the shafts 11 and 12. Each of these shafts is provided with its own bearings mounted on the bed-plate so that the alignment of one is independent of that of the other. By locating the shaft bearings on opposite sides of the wheel casing and making them of generous dimensions, I avoid the troubles due to alignment and also those which would be experienced if the shafts were telescoped. Where the shafts pass through the walls of the casing, packings 13 are provided to prevent the escape of fluid when the pressure is above that of the atmosphere and to prevent the entrance of air when the pressure is less. These packings can be of any well known construction, those shown comprising carbon rings 14 closely encircling the hubs with springs 15 between, which press them against the stationary seats 16 and 17. The second stage of such a machine is similar in construction to the first except that the nozzles or other fluid discharging devices and bucket passages are made somewhat larger to accommodate the increased volume of motive fluid.

In Fig. 2 is shown a two-stage three-generator unit combination wherein each of the end units develops about fifteen per cent. of the total, and the intermediate unit about seventy per cent. The intermediate unit is of the induction type and the end units of the synchronous type. Steam or other fluid enters the left-hand stage of the turbine by the conduit 8, flows through the primary bucket wheel that is connected to the rotating member of the main generator unit 18 and through the secondary bucket wheel connected to the left-hand generator unit 19. After exhausting from the secondary wheel the fluid is conveyed to the nozzles of the second stage by the conduit 7. For the purpose of illustration these conduits are shown above the turbine and generators, but obviously they may be located wherever it is the most convenient. After the pressure of the motive fluid is converted into velocity by the second-stage nozzles it acts on the wheel buckets and the latter abstract the energy thereof by successive operations. The fluid exhausting from the second stage is conveyed by the conduit 20 to a condenser or to other exhaust. The primary wheel of the second stage is connected to the rotating member of the main generator unit 18 and the secondary wheel to the rotating member of the right-hand generator unit 21.

In Fig. 3 the arrangement of the parts has been changed to give a different distribution of energy. Here the center generator unit is of the induction type and is driven by one

primary and one secondary wheel of the two stages, and as a result gives about fifty per cent. of the total output. The generator unit 19 is of the synchronous type and is driven by a secondary wheel as before, and so its output remains unchanged at about fifteen per cent. of the total. The generator unit 21 is of the induction type and is driven by a primary wheel and therefore is larger than before and has an output of about thirty-five per cent. of the total. In this case the unit 19 can supply the exciting current for the other units.

In Fig. 4 is still a different arrangement. Here the center generator unit 18 is driven by two secondary wheels and has an output of about thirty per cent. of the total while both the end generator units are driven by primary wheels, and each has an output of about thirty-five per cent. of the total. Such a combination is well adapted for direct-current units.

In Fig. 5 another arrangement is shown, wherein the generator unit 19 is driven by a primary wheel as before and the generator unit 18 by one primary and one secondary wheel and the third generator unit 21 by a secondary wheel. In this arrangement the generator unit 19 has a capacity equal to about thirty-five per cent. of the total, unit 18 about fifty per cent. and unit 21 about fifteen per cent.

In Fig. 6 is shown a diagram of connections of the generator units above referred to and illustrated in Fig. 3. These units are of the three-phase synchronous and induction alternating-current types, and the diagram is typical of the connections for the groups or arrangements of induction and synchronous units shown in the other figures. Each armature winding is connected by three connections 22, 23 and 24 to the conductors 25, 26 and 27, which may be the bus-bars on a switch-board for example.

The synchronous generator can be excited from a suitable source of direct current 28.

In Fig. 7 are shown three direct-current generator units 29, 30 and 31 with armature taps 32 120° apart which are connected by wires through slip-rings 33 with each other and form a three-phase electrical gearing between the generators to maintain the proper speed relation. With this arrangement, as in the one previously described, it is only necessary to govern the admission of motive fluid to one of the stages.

In Fig. 8 is shown an induction type of alternating current unit suitable for the purposes described. It comprises a squirrel-cage rotor 34 and a field magnet 35 having a winding thereon with three taps 36 connected with a source of alternating current supply.

In Fig. 9 is shown a synchronous type of

alternating current unit suitable for the purposes described. It comprises a stationary armature structure 37 and a revolving field magnet structure 38 having a winding 39 thereon supplied by some direct current source of supply.

I have shown each of the wheels provided with a single row of wheel buckets, since it is ideally simple in construction, but the invention is not to be construed as being limited thereto unless so stated specifically in the claims, because many of the advantages of my invention will follow where each wheel is provided with two or more rows of buckets either with or without stationary intermediate buckets. By using a greater number of wheel buckets and the same spouting velocity of the motive fluid, other things being equal, I can obtain a lower shaft speed than where each wheel has only a single row of buckets.

In some cases it will be desirable to use intermediate buckets for the purpose of getting a better angle of entrance to the buckets of the secondary wheels. By suitably shaping these buckets the wheels may be made to revolve in opposite directions, or by a change in shape they may be made to revolve in the same direction. Irrespective of the direction of rotation imparted to the wheels, the benefits of my invention in so far as the generator is concerned, will follow.

By dividing the generator into units and mounting the movable member of each unit on its own shaft, which shaft is entirely independent of each of the others, I am able to construct a larger generator for a given shaft speed with units of standard and conservative design than has heretofore been possible.

By dividing the generator into units and arranging them in the manner specified, I am able to utilize that type of generator unit which is best adapted for the given output and shaft speed, and by properly directing the steam or other elastic fluid thereto, each unit will perform its share of the work. I regard the idea of sub-dividing the generator in this manner as being a very important advantage both from an electrical and mechanical standpoint. By utilizing three independent shafts in the manner specified, troubles due to the alinement and lubrication are reduced to a minimum, and each electrical unit and its driving member can readily be assembled or taken down. The shafts can be made relatively short thereby avoiding the whipping action found with long shafts and the bearings can be made of a size best adapted for the work and located where they are readily accessible.

The invention is shown in connection with a turbine having parallel-flow stages, but it is not necessarily limited thereto, since the

motive fluid can flow in another direction or directions. The turbine shown acts on the impact principle, but under certain conditions it may act by reaction or by a combination of impact and reaction.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

15 What I claim as new and desire to secure by Letters Patent of the United States, is,

1. A turbine comprising stages each having bucket wheels, in combination with a member located between the adjacent wheels 20 of the different stages and driven thereby, and other members located on the opposite side of said stages and driven by the outer wheels.

2. A turbine comprising stages each having bucket wheels, in combination with a member driven by two of said wheels and other members each driven by an individual wheel.

3. A turbine comprising stages each having bucket wheels, in combination with a member driven by a pair of said wheels located in different stages and other members driven by individual wheels, and means for controlling the rotation of said members.

35 4. A turbine comprising stages each having oppositely rotating bucket wheels, in combination with a member driven by a pair of said wheels and other members driven by individual wheels, and means connecting the several wheels in such a manner as to control their speed relation.

5. A turbine comprising stages, each containing a primary and a secondary bucket wheel which develop unequal torque and shafts therefor, in combination with members driven thereby, one of which is mounted on the shaft connecting two of said wheels while each of the other members is driven by an individual wheel, the shafts for which 50 extend in opposite directions.

6. A turbine comprising stages each having oppositely rotating bucket wheels, in combination with power-transforming units driven thereby, one of said units being connected to a greater number of wheels than another, and connections between the units for controlling their speed relation.

7. A turbine comprising stages each having bucket wheels, in combination with members driven thereby which require unequal amounts of power, the largest of said members being located between two wheels and driven by both while the others are each driven individually by a wheel.

8. A turbine comprising stages each having bucket wheels, shafts therefor, and independent bearings for each shaft, in combination with power-transforming units driven thereby which develop unequal amounts of energy at the same shaft speed, the largest 65 of said units being driven by a greater number of bucket wheels than the others, the shaft for the largest unit being located between those of the other units and independent thereof.

75 9. A turbine comprising stages each having oppositely rotating bucket wheels, in combination with power-transforming units driven thereby which develop unequal amounts of energy at the same shaft speed, 80 and connections between the units to control their shaft speed.

10. A turbine comprising stages each having individual primary and secondary wheels which develop unequal torque at the 85 same shaft speed, in combination with individual members driven thereby, one of said members being driven by primary wheels, and a means for controlling the speed of the wheels and said members.

90 11. A turbine comprising stages each having individual primary and secondary wheels which develop unequal torque at the same shaft speed, in combination with individual members driven thereby, one of said 95 members being driven by primary wheels, the others by secondary wheels, and means connecting the several wheels in such manner as to control their speed of rotation.

12. A turbine comprising stages each 100 having individual primary and secondary wheels which develop unequal torque at the same shaft speed, in combination with individual power-transforming units driven thereby which produce unequal amounts of 105 energy at the same shaft speed, and connections which unite the units and control the speed of rotation of them and their connected wheels.

13. A turbine comprising stages each 110 having oppositely rotating wheels, in combination with a member driven by wheels of both stages, and other members driven individually by the remaining wheels of said stage.

115 14. A turbine comprising compartments each having individual wheels mounted therein, a shaft for a pair of wheels, and individual shafts for the remaining wheels, in combination with a member driven by 120 the shaft connected to the pair of wheels, other members driven separately by the individual shafts, and means for causing the shafts to rotate synchronously or substantially so.

125 15. A turbine comprising stages each having oppositely rotating wheels, a shaft common to certain wheels of both stages, in

dividual shafts for the other wheels, independent bearings for the shafts, and a bed-plate common to the bearings, in combination with a power-absorbing unit for the 5 shaft which is common to wheels of both stages, and other power-absorbing units, one for each of the other shafts.

In witness whereof, I have hereunto set my hand this 19th day of April, 1907.

ERNST J. BERG.
